J. FEIG

GIRDLE

Filed Dec. 16, 1924

Patented Oct. 5, 1926.

UNITED STATES PATENT OFFICE.

JULIA FEIG, OF BALTIMORE, MARYLAND.

GIRDLE.

Application filed December 16, 1924. Serial No. 756,252.

This invention relates to a novel and improved construction of girdle designed for the purpose of giving support to the portions of the body which it encompasses and 5 confining the figure so as to secure a trim and shapely outline contour of and appearance to the buttocks, hips and abdominal portions of the body of the wearer, also to the waist, if desired.

10 The primary object of the invention is to provide a girdle which is so constructed and provided with means adapting it to be adjusted to hold the aforesaid portions of the body shapely without discomfort to the 15 wearer and so as to give to such portions of the body a proper outline contour and a trim and pleasing effect.

A further object of the invention is to provide a girdle which will serve as a shaping 20 form over which the outer garments of the wearer will fit in such manner as to give to the figure of the wearer and the dress or outer garment, of whatever style worn, the desired "straight line effect" irrespective of 25 any peculiarities of shape of the portions of the body of the wearer over which the girdle is worn, without causing discomfort or inconvenience to the wearer.

A still further object of the invention is 30 to provide a girdle which is simple of construction, easy of application and removal, adapted to be worn with maximum comfort and without harmful effects, and which reduces to a minimum the number of lacings 35 or other adjustable fastenings required, so as to avoid bulkiness of appearance at any point.

A still further object of the invention is 40 to provide a girdle which may be so shaped to the form above and below the hip line as to be self-supporting against any possibility of casual slipping up or down on the person of the wearer.

In the accompanying drawing,—

45 Figure 1 is a front perspective view of a girdle constructed in accordance with my invention, the same being shown as arranged to be worn.

Figure 2 is an inner face view of the girdle 50 outspread.

Figure 3 is a detail section on the line 55 3—3 of Figure 2.

Referring now more particularly to the drawing, the girdle comprises a back section

A, two front sections B and C, and two intermediate sections D.

The back section A is of unitary character and of a length to extend across the buttocks and small of the back to and over the sides of the hips, and of a depth, in case of a girdle, to extend from a point at or adjacent to the waistline down to a desired distance below the curves of the hips. This section A is made of fabric or other suitable flexible but non-elastic material, and may be provided with flexible bones or stays A' extending the full depth thereof and arranged as shown so as to impart to said section a desired degree of stiffness, while allowing it to have ample flexibility to conform to the 70 shape of the portions of the body against which it lies.

The front sections B and C are adapted to overlie the front of the figure between the center line of the abdomen and the groin 75 lines and, like the back section A, are of unitary construction and made of fabric or other suitable inelastic but flexible material; and the front or meeting edges of these sections B and C are provided with suitable fastening means for connecting them together and holding the garment in girdle form about the person. Such fastening means may be of a type to be readily engaged and disengaged, and such for example as 80 that shown, to wit, loops B' on the meeting edge of one front section to engage headed studs C' on the meeting edge of the other front section. Each front section is provided with a reinforced upper portion and a 85 non-reinforced lower portion, secured by providing such section with flexible bones or stays C'. These bones or stays, as shown, extend from the upper edge of the section downwardly to a point adjacent to or somewhat below the medial horizontal line of the section as shown at C'. By this construction the upper portions of the sections B and 90 C are flexibly reinforced to adapt them to conform to the protuberant contour of the upper portion of the abdomen and to give effective support thereto, while the lower portions of said sections are left without stays and freely flexible so as to be readily drawn inwardly to conform to the shape of the receding lower portion of the abdomen.

95 The elastic sections D are made of elastic webbing or other suitable elastic material.

They are arranged to extend over the groins and front portions of the sides of the hips, between the rear edges of the respective front sections and the front edges of the hip portions of the back section, and to connect said sections so as to permit the garment to be extended for application to the person and then, by re-action of said elastic sections, to be contracted to draw the fastened garment closely and snugly about the person. As shown, each elastic section D is in the form of a continuous piece of material of a length to extend the full depth between the upper and lower edges of the garment, being permanently united at its front edge to the rear edge of the contiguous front section and permanently united for a distance at the upper portion of its rear edge to the upper portion of the edge of the front section with which it connects, as hereinafter fully described. Preferably each elastic section tapers slightly in a longitudinal direction between its lower and upper ends, making the upper portions of said elastic sections somewhat less elastic than the lower portions, so as to give greater resistance to the extension of the upper portion of the garment fitting over the hips and across the small of the back and over the protuberant portion of the abdomen. For the purpose of increasing this elastic resistance to the extension of the upper portion of the garment, I may also provide supplementary strips D' of elastic webbing or other elastic material extending transversely of the upper ends of the sections D and sewed at their upper edges thereto and at their side edges to the edges of the front and back sections. These supplementary strips may be of any desired degree of elasticity for a proper supplementary or added resistance action. By this construction the greater portions of the elastic sections D are permitted to extend and contract with necessary freedom to draw the garment snugly about the body of the wearer, and adapt the same to permit free and easy body movements of the wearer, while the added resistance to extension and increased contractive pull exerted by the strips D' prevents undue free expansion of the upper margin of the garment, thereby holding the upper ends of the meeting edges of the front sections closely against the body and preventing any tendency of the garment to gape or jut objectionably forward from the body at this point, particularly when the wearer sits down.

The edges of the hip portions of the back section A and rear edges of the elastic intermediate sections D are fixedly united, as at E, at their upper portions for a distance of about one-fourth, more or less, of their length along lines which extend from points immediately above the crests of the hips to the upper or waist line edge of the garment,

but below these fixed points and between the same and their lower edges are divided or left disconnected to provide separated edges E', said separated edges having holes or eyelets for the passage of adjustable connections, such as lacings F, whereby such separated edges may be adjusted with relation to each other. By this construction the upper portion of the garment above the horizontal line of the divided lower extremities of the fixed portions E, which portion of the garment is of less elasticity and expansibility than the portion of the garment below, may be definitely formed to snugly and automatically assume the contour of the portion of the body which it encompasses above the hip line without adjustment of laces or other adjusting means, the elasticity of the contiguous portions of sections D taking up any undue fullness or permitting any necessary expansion of such portion of the garment, to adapt it to take a snug fit without manipulation of adjusting means, while the aforesaid lower portion of the garment of greater elasticity and expansibility is adapted to be adjusted by the laces along the vertical lines of the sides of the hips to draw upon such lower portion of the garment so as to snugly fit and give a trim contour to the portions of the body which it encompasses. It will therefore be seen that the said upper portion of the garment of minor elasticity and expansibility may by its own elasticity assume at the front the protuberant contour of the upper portion of the abdomen and at other points the concaved shape of the body over the hips and around the small of the back, while the lower portion of the garment of greater or major elasticity and expansibility may be adjusted to conform to the receding curvature of the lower portion of the abdomen and the convex and compound curvatures of the hips, buttocks and groins, and whereby also the lower edge of the portions of the garment overlying the hips will be contracted and extend inwardly below the major point of curvature of the hips, this upper and lower shaping of the garment thereby utilizing the crest curvature of the hips as points of abutments whereby, in addition to the snug and trim fit secured, the garment will be effectually held from vertical movement, namely, prevented from shifting upwardly or downwardly on the person of the wearer and causing either discomfort or embarrassment. In other words, the described construction of the garment adapts it not only to be fitted to snugly encompass the portions of the body to which it is applied, and to support and hold such portions shaped in order that a pleasing and trim outline may be secured, but the garment is rendered self-supporting in position without the necessity of employing additional or extraneous means for the purpose.

My improved girdle, constructed as above described, is designed to be used for the purpose of providing a shaping form over which the outer garments of the wearer may be draped to give a desired "straight line effect" to the figure and especially to the figures of those persons of the female sex having a slight tendency to corpulency.

To this end, it is necessary that the girdle 10 be so constructed that the waist portion will maintain its form as a building out member as against any tendency to cause it to taper or lose its outline shape in its expansions or contractions or under forces caused by 15 motions of the lower portion of the girdle in its expanding and contracting movements incident to walking movements and other movements of the lower limbs of the wearer. By permanently uniting the sections 20 A—B—C along the lines E that portion of the garment which encircles the waist may be given a permanent outline form, such that the waist-portion of the girdle will be generally of greater diameter than the waist 25 of the body of the wearer, touching the body at the most protuberant parts of the body and standing away from those portions of the body which recede the most, so that the concaved curvature of the waist portion of 30 the girdle will be less than that of the waist portion of the body proper, giving, therefore, a vertical or straight line effect vertically across the waist and between the chest and the hips. In order to maintain this 35 shape it is necessary that such waist-portion of the girdle be stiff enough to be self-supporting, flexible enough to permit bending movements of the wearer without discomfort, and elastic enough to permit of a certain amount of expansion and contraction. These requirements are obtained by the permanent connections E which prevent independent movements of the sections A, B and C at their points of juncture in the waist-portion of the girdle, and by the comparative stiffness and stability and resistance to buckling of the adjoining upper portions of the unitary elastic sections D. The addition 45 of the elastic sections D' is of advantage in this connection in giving increased stiffness at these points against deformation of the waist portion of the girdle, and such sections D' also as stated, give increased resistance to diametric expansion of the girdle 50 so as to hold the upper front ends of the fastened meeting edges of the sections B—C drawn in when the wearer sits down, thus preventing protrusion and gaping at the front of the garment. While, as stated, the 55 waist-portion of the girdle should maintain a fixed and definite shape for the straight line effect, it is required that the portion of the girdle below the crests of the hips be made adjustable, in order that the flabby 60 flesh over the abdomen, hips and buttocks

may be drawn in for form reduction and molding into shape to give as far as possible straight line effect from the waist downward. This is permitted by the elasticity of the portions of the sections D below the line of the crests of the hips and by the provision of the separated edge portions E' and the laces F adjustably connecting the same. By drawing upon these laces, after the garment has been fitted in position and secured by the fastenings B'—C', that portion of the girdle lying below the line of the crests of the hips may be adjusted to snugly fit the body and draw in or mold the surplus flesh, in which operation the portions of the elastic sections from the line of the crests of the hips downward will be stretched and placed under tension, thus holding the molded portions of the body elastically confined. When so applied it will be apparent that the tensioned elastic sections will keep the girdle snugly in position while allowing ample freedom of body movements. It will be noted that such adjustment of the edge portions E' and tensioning of the lower portions 65 of the elastic sections D will be permitted without affecting in any material manner the shape of the waist portion and the portions of the sections D comprised therein, since the fixed connections at the points E prevent any relative motion between the meeting edges of the sections A—D above the separated edge portions E'. Hence the edge portions E' may be adjusted and have relative movements with the adjoining portions 70 of the elastic sections D without expanding, contracting, tapering or otherwise changing the form or dimensions of the waist portion of the girdle, so that this portion of the girdle will maintain its shape while necessary working motions of the lower portion 75 of the girdle are freely permitted under body movements of the wearer. These functional qualifications of my straightline effect girdle could not be obtained if the edges 80 of sections A—D were separated and connected by the laces F the full depth of the girdle, for the reason that adjustment of the lower portion of the girdle could not be made without correspondingly affecting the waist portion of the girdle. The permanent connections at the points E are also advantageous over separated edges and connecting laces at these points, since such laces would 85 be subjected to working motions and loosened and stretched under body movements of the wearer and adjustments of the edge portions E' by the laces F, thus allowing undesirable movements and changes of shape 90 of the waist portion of the girdle. The permanent connections E further permit permanent shaping of the waist portion of the girdle where it comes over the crests of the hips to prevent the girdle from working 95 downward on the body of the wearer, while 100

the structural formation of the edges E' and their lacing connections permit adjustment of the lower portion of the garment to place it under proper tension, as circumstances 5 may require in individual cases, to cause the girdle to underlie the bases of the hips and thus prevent the garment from working upward on the body of the wearer.

It is obvious that a corset embodying the 10 novel and desirable features of my invention may be produced by extending the upper edges of the girdle upwardly to a desired degree to form a corset structure proper, and this modification is held to fall within the 15 spirit and scope of my invention.

From the foregoing description, taken in connection with the drawing, the construction and mode of use of my improved girdle will be understood, and it will be seen that 20 the invention provides a girdle having flexible, elastic and inelastic portions, combined with adjustable portions, so arranged as to enable it to be accurately shaped to a desired supporting contour, while adapting it to 25 maintain itself in position without fastening means auxiliary to the garment itself. Also it will be seen that the invention provides a garment in which the features mentioned are so combined and arranged as to prevent gapping 30 or protrusion of the garment at any point objectionably beyond the body lines. The construction described further enables a one-piece back section to be employed and the use of back lacings to be avoided, and a 35 reduced number of lacings at restricted points to be employed, by which the use of certain adjusting means of essential type but liable to protrude and cause bulkiness at points is reduced to a minimum extent, so 40 that a smooth fitting of the clothing over the corset or girdle may be secured and the established outline contour formed by the girdle preserved. It will also be seen that, as 45 the garment avoids the use of non-porous rubber or its equivalents, and is constructed in the main of porous fabric and webbing, it may be made light in weight, of sufficient flexibility and elasticity in character to adapt 50 it to conform readily to the body movements, and to be worn in summer as well as in winter without causing excessive perspiration, so that the garment may be used at all times 55 without inconvenience or discomfort to the wearer.

55 The garment may be provided with hose supporters G of any suitable type if desired.

Having thus fully described my invention, I claim:—

1. A girdle which encircles the body between the waistline and the line of the lower portion of the abdomen, said girdle comprising an inelastic back section, inelastic front sections, unitary elastic intermediate sections vertically continuous between the top and bottom edges of the girdle, each intermediate section being permanently secured at its front edge to the rear edge of the contiguous front section and permanently secured at its rear edge to the front edge of the contiguous back section along a line extending from a point adjacent to and above the crest of the hip to the upper edge of the garment, the latter-named edges of the intermediate and back sections thence being separated downwardly to and through the lower edge of the girdle, and laces adjustably uniting the separated edges of the back and intermediate sections below their lines of permanent connection.

2. A girdle which encircles the body between the waistline and the line of the lower portion of the abdomen, said girdle comprising an inelastic back section, inelastic front sections, unitary elastic intermediate sections vertically continuous between the top and bottom edges of the girdle, each intermediate section being permanently secured at its front edge to the rear edge of the contiguous front section and permanently secured at its rear edge to the front edge of the contiguous back section along a line extending from a point adjacent to and above the crest of the hips to the upper edge of the garment, the latter-named edges of the intermediate and back sections thence being separated downwardly to and through the lower edge of the girdle, laces adjustably uniting the separated edges of the back and intermediate sections below their lines of permanent connection, and a contractile transverse elastic strip extending across each elastic intermediate section adjacent to and parallel with the waistline and terminally secured at the ends thereof to the contiguous portions of the permanently united edges of the intermediate section, said strips elastically reinforcing said intermediate sections to give added resistance to expansion of the upper waist-encircling portion of the girdle.

In testimony whereof I affix my signature.

JULIA FEIG.
